UNITED STATES PATENT OFFICE.

THOMAS TEMPLE, OF HUDSON, MICHIGAN.

HAY-ELEVATOR.

SPECIFICATION forming part of Letters Patent No. 339,496, dated April 6, 1886.

Application filed July 8, 1885. Serial No. 170,983. (No model.)

To all whom it may concern:

Be it known that I, THOMAS TEMPLE, a citizen of the United States, and a resident of Hudson, in the county of Lenawee and State of Michigan, have invented certain new and useful Improvements in Hay-Elevators; and I do hereby declare that the following is a full, clear, and exact description of the invention, which will enable others skilled in the art to which it appertains to make and use the same, reference being had to the accompanying drawings, which form a part of this specification.

My invention consists in the improved construction and combination of parts of a hay-elevator which possesses advantages in the points of simplicity of construction and efficiency in operation which will be hereinafter fully described, and particularly pointed out in the claims.

Referring to the annexed drawings, Figure 1 is a side view showing my improved hay-elevator arranged in its operative position, one side of the box or casing in which the free ends of the slings are detachably secured being partially broken away to illustrate the construction and arrangement of the several parts. Fig. 2 is a side view of the slings in which the bundle of hay is secured and their adjacent parts, the sides of the box or casing in which the free ends of the slings are detachably secured being broken away to illustrate the construction and arrangement of the several parts. Fig. 3 is a detail view in perspective of one of the coupling devices which connect the upper ends of the slings to the lower ends of the draft or elevator ropes; and Fig. 4 is a detail view of the spring-clutch I.

The same letters of reference indicate corresponding parts in all the figures.

Referring to the several parts by letter, A represents a supporting-rope, which is provided at its lower end with a suitable pulley, A', over which runs the draft or elevating rope, the rope A being of such a length, and being secured at its upper end to one of the rafters of the barn in which the hay is being stored at such a point, as to permit of the bundle of hay which is elevated in the slings being swung immediately over the mow, where it is released from the slings through the mechanism which will be hereinafter described.

B represents the single draft or hoisting

rope, which passes over a suitable pulley, B³, secured at a point a little above the hay-mow, and then over the pulley A', secured on the lower end of the supporting-rope A, that portion of the rope which passes over the pulley A' having connected to it the double draft-rope B², to the ends of which are attached the upper ends of the slings D D.

C indicates the box or casing through which the double draft-ropes pass, and in which the free ends of the slings D are detachably secured, the said casing having journaled in each end a pulley, C' C', under which the double draft-ropes run. Between these pulleys C' C' is centrally pivoted a key-lever, C², the lower portion of which is bent at right angles to the main vertical portion, and the free extremity of this horizontal lower portion comes in close proximity to a stop or projection, c', formed transversely in the casing C, as shown, a spiral spring, C³, serving to hold the key normally in this closed position, with the extremity of the arm c in contact with the projection c'. An operating-cord, C, is secured at one end to the upper extremity of the key-lever C², by means of which the said lever may be swung into its open position, as shown in dotted lines in Fig. 2 of the drawings, for the purpose hereinafter specified.

To the lower ends of the double draft-rope B² are connected, by means of the coupling devices E E, (the construction of which will be hereinafter described,) the slings D D. These slings are formed of rope or other suitable material, and are adapted to be secured around the bundle of hay which it is desired to elevate from the wagon upon the hay-mow, each of the said slings being formed at its free end with a loop, D', as shown. A short band, F, of suitable material is secured at one end in the casing C, and is provided at its free end with the link or ring F', adapted to fit around the lower horizontal portion of the key-lever C², when the latter is in its closed position. A short chain may be employed in place of the band F, when desirable.

To the lower end of the supporting-rope A, near the pulley A' of the same, is secured the upper end of an auxiliary rope, G, which passes over a pulley, G', which is secured at a point about in the same plane as the pulley

B^3 , but on the opposite side of the supporting-rope, the auxiliary rope G having secured to its lower free end the weight H , which serves to bring the box or casing C and the slings 5 $D D$ back from the top of the mow, after the bundle of hay has been deposited thereon, down over the hay-wagon. A spring-clutch, I , having a releasing-cord, I' , is secured near the pulley G' and serves to clutch and hold 10 the rope G while the bundle of hay is being elevated in a vertical line until it reaches the pulley A' on the lower end of the supporting-rope A , when the spring-clutch is released or 15 opened by pulling upon its cord I' , and the bundle is permitted to swing toward and over the mow.

The coupling devices $E E$, which serve to connect the upper ends of the slings D to the ends of the double draft-rope, consist each of 20 a link formed of two sections, E' and E^2 , the section E' being formed with the shoulder E^3 and the projection or key E^4 , having at its extremity the enlargement E^5 , while the section E^2 is provided with the longitudinal aperture 25 E^6 , oval in cross-section and of such a size as to admit of the insertion of the oval head E^5 of the key or projection E^4 when the latter is turned to register with the said opening; but after the key has been inserted 30 through the said aperture it is turned at right angles, so that its oval head lies across the upper edges of the aperture, as shown, thereby preventing the coupling from separating, while at the same time it may be easily unfastened when desired. The upper edges of 35 the section E^2 at the upper end of the aperture E^6 are slightly grooved transversely, at E^8 , to form a seat for the ends of the oval head E^5 , after the same has been turned into 40 its locked position. A rubber tension-plate or washer, E^7 , is seated upon the shoulder E^3 of the section E' , and serves as a spring to hold the coupling in its locked position and prevents the sections from working apart or 45 loose from one another, this rubber disk yielding slightly as the coupling passes under or through the pulleys $C C'$ in the box or casing C , as the bundle is being elevated, and thereby prevents any extra strain or friction between 50 the couplings and the said pulleys.

A tension-spring, J , having its lower free end slightly curved, is secured to one side of the box or casing C , and to the side of the rack upon the hay-wagon is secured a cord, J' , provided with a loop, J^2 , at its free end, adapted to fit around the lower curved end of the tension-spring J , for the purpose which will be hereinafter fully described.

The operation of my improved hay-elevator 60 is as follows: The elevator having been adjusted in the position shown in Fig. 1 of the drawings, the free ends of the slings $D D$ are passed around the bundle of hay, and the band F is then drawn through the loops on 65 the said ends, the link or ring F' on the end of the said band being then slipped over the horizontal lower portion of the lever-key C' ,

when the spiral spring C^3 draws the key back into its closed position, thereby holding the free ends of the slings firmly in the box or 70 casing while the bundle is being elevated to the top of the hay-mow. The loop on the end of the cord J' is then slipped over the lower curved end of the spring on the side the box or casing C , and the spring-clutch I is allowed 75 to grasp the weight-rope G at such a point as to hold the supporting-rope A in a vertical position. By applying the necessary power to the lower end of the single draft-rope B the bundle will be now elevated, the cord J' serving to hold the box C stationary until the slings have tightened firmly around the bundle, when the free curved end of the spring J yields sufficiently to cause the loop on the end of the cord J' to slip off, thereby releasing the 85 box C after the bundle has been tightly bound by the slings, while if this device were not used the bundle of hay would not have sufficient weight to cause the slings to tighten around it, and there would be danger of its 90 slipping loose and falling out of the slings. When the bundle has been elevated until the box or casing C comes in contact with the pulley A' on the lower end of the supporting-rope A , the spring-clutch I is released by pulling 95 upon the cord I' , when the draft-rope operates to swing the bundle to one side over the hay-mow, the rope G running through the pulley G' to admit of this movement. When the bundle is immediately over the mow, the 100 operating-cord C^4 is pulled, thus opening or drawing back the key-lever C^2 and releasing the end of the band F , which in turn frees the lower ends of the slings $D D$, thereby releasing the bundle of hay and allowing it to drop 105 upon the mow in its appropriate position. The weight H then operates to bring the box or casing C and the lower end of the supporting-rope A back into their former positions over the wagon, when the operations just described 110 are repeated.

From the foregoing description, taken in connection with the accompanying drawings, the construction and operation of my improved hay-elevator will be readily understood without requiring further explanation.

It will be seen that my improved elevator is simple in construction, being devoid of all complicated parts which are liable to break or get out of order, while at the same time it is 120 very efficient in its operation.

Having thus described my invention, what I claim, and desire to secure by Letters Patent of the United States, is—

1. As an improvement in hay-elevators, the 125 combination, with the draft-ropes and the slings having the loops formed at their free ends, of the box or casing having the two pulleys journaled therein at each end and formed with a transverse projection between the said 130 pulleys, the key-lever centrally pivoted within the said casing, and having the operating-cord and the short band or chain secured at one end in the said casing, and provided at its

free end with a link or ring, all constructed and arranged to operate in the manner and for the purpose shown and set forth.

2. As an improvement in hay-elevators, the 5 combination, with the draft-ropes and the slings having the loops formed at their free ends, of the box or casing having the two pulleys journaled therein at each end and formed with the end tension-spring having the lower 10 curved end and the transverse projection between the said pulleys, the key-lever centrally pivoted within the said casing and provided with the operating-cord, the short band or chain secured at one end in the said casing 15 and provided at its free end with a link or ring, and the tension-cord adapted to be fastened at one end to the rack on the hay-wagon and provided at its other or free end with a loop adapted to fit over the lower curved free end 20 of the tension-spring on the end of the box or casing, all constructed, combined, and arranged to operate in the manner and for the purpose shown and described.

3. The combination of the supporting-rope 25 having the pulley at its lower end, the draft-ropes arranged as described, the slings having the loops formed at their free ends, the box or casing having the pulleys journaled therein at each end and formed with a transverse projection between the said pulleys, the key-lever 30 centrally pivoted within the said casing and provided with the operating-cord, the short band or chain secured at one end in the said casing and provided at its free end with a link 35 or ring, the auxiliary rope passing over a pulley, arranged as described, and provided at

its lower free end with a suitable weight, and a spring-clutch having a releasing-cord and adapted to engage with the said rope for the purpose set forth, all constructed, combined, 40 and arranged to operate in the manner and for the purpose herein shown and specified.

4. The combination of the supporting-rope having the pulley at its lower end, the draft-ropes arranged as described, the slings having the loops formed at their free ends, the box or casing having the pulleys journaled therein at each end and formed with the end tension-spring having the lower curved end and the transverse interior projection, the key- 45 lever centrally pivoted within the said casing and provided with the operating-cord, the short band or casing secured at one end in the said casing and provided at its free end with a link or ring, the tension-cord having the loop 50 at its free end and adapted to be arranged as described, the auxiliary rope, arranged as described, and having a suitable weight at its lower free end, and the spring-clutch having a releasing-cord and adapted to engage with 55 the said rope, all constructed, combined, and arranged to operate in the manner and for the purpose shown and set forth.

In testimony that I claim the foregoing as my own I have hereunto affixed my signature 60 in presence of two witnesses.

THOMAS TEMPLE.
